United States Patent Office

Des. 188,429
Patented July 19, 1960

188,429

BREAD BOX

John W. Ebstein, Roslyn Heights, N.Y., assignor to Federal Enameling & Stamping Co., Pittsburgh, Pa., a corporation of Michigan

Filed Mar. 30, 1960, Ser. No. 59,955

Term of patent 14 years

(Cl. D44—6)

FIG. 1.

FIG. 2.

Figure 1 is a view in perspective of my novel bread box, the rear is substantially plain and the side opposite that which appears in the view is identical.

I claim:

The ornamental design for a bread box, as shown and described.
